ADJUSTABLE CLIP SUPPORT FOR
TOOTHBRUSHES

Nathan A. Oscher, Brooklyn, N. Y.

Application June 4, 1948, Serial No. 31,104

1 Claim. (Cl. 24—261)

1

My invention relates to toothbrushes and more particularly to a device adapted to be attached to the handle of a toothbrush for the purpose of supporting the brush in the conventional toothbrush holder.

My principal objective was to construct a device that could be affixed to a toothbrush handle so that the brush would be supported in a manner that would prevent the bristles from contacting other brushes, thereby preventing the spread of any contagious diseases.

A further objective was to support the brush in such a manner that the bristles would be able to drain and dry and would not remain soggy through direct contact with the upper surface of the toothbrush holder.

An advantage of my invention is that it is adapted to fit any type and shape of toothbrush handle and is so constructed that it may be placed in any desired position on the handle.

Another advantage is that my device serves as a gripping means for the user when the teeth are being brushed.

My device is also simple in construction and economical to manufacture.

Further advantages and unique features of my invention will be apparent as I proceed with the description.

With reference to the drawings:

Fig. 1 is a side elevation showing toothbrushes equipped with my device disposed in a conventional holder;

Fig. 2 is an enlarged side view of my device secured to a toothbrush handle;

Fig. 3 is an enlarged front view of my device secured to a toothbrush handle;

Fig. 4 is a sectional view on line 4—4 of Fig. 3;

Fig. 5 is a perspective view of my clip support;

Fig. 6 shows a modified form of my clip support;

Fig. 7 shows my clip support equipped with an identification plate.

With reference to the drawings, my clip support 10 consists of a single piece of resilient wire shaped to a desired configuration. As shown in Fig. 5, the preferred form of my support 10 provided two spaced and inverted U-shaped members 11 and 12 with downwardly depending arm portions 13. The center portions 14 of the bight as shown in Fig. 4 are substantially parallel to each other and are so designed that the space between them is narrower than the toothbrush handle 15 so that when the device 10 is applied to the handle, the bight portions 14 will engage in the notches 16 securely clamping the device 55

2

to the handle. The ends of the bight portions 14 are flared out forming curved projections which engage on the upper surface 18 of the conventional toothbrush holder 19, thereby supporting the brush in any desired position.

As shown in Fig. 3, the depending arm portions 13 of the U-shaped members 11 and 12 taper inwardly and towards each other, and the arm portions 13 of the U-shaped members 11 and 12 are joined to each other at their lower ends by curved sections 20. The sections 20 are curved to adapt themselves to the shape of the handle 15 and these sections also engage in notches 21 positioned on the sides of the handle.

15 As indicated by the drawings, the device in its preferred form is made from a single piece of resilient wire. In use, the device 10 is placed on the handle 15 of a toothbrush as shown in Fig. 1 so that the bight portions 14 of the U-shaped 20 members and the curved sections 20 engage in the notches 16 and 21 respectively on the front and rear, and sides of the handle.

25 The modification 40 shown in Fig. 6 is also made from a single piece shaped to provide an inverted U-shaped member 30 and downwardly and upwardly extending arm portions 31 and 32 respectively. The free ends of the device are then bent downwardly and then upwardly forming two pairs of loops 33 and 34 while the ends 35 extend vertically upward forming right members 35 that rise above the bight of the U-shaped member 30. The extreme ends 36 of the upright members 35 are bent inwardly so when the bight of the U-shaped member 30 is engaged in the notch 16 on the handle 15, the ends 36 will exert pressure against the opposite side of the handle to clamp the device 40 in position.

When the toothbrush is placed in the opening 22 provided in the conventional holder 19, the projections 17 will engage the upper surface 18 of the holder, thereby supporting the brush in an upright position. As the toothbrush handle 15 will be provided with a plurality of notches 16 and 21 on the front, rear and side portions, the device may be adjustably secured to any position on the handle. Furthermore, as shown in Fig. 1, the device may be conformed to accommodate brushes with curved handles.

30 As an additional feature of my device, in Fig. 7 I have shown how it may be equipped with an identification name plate 50 which may be readily attached to the device and which in no way would interfere with the operation or function of the device.

35 While the invention has been described in de-

tall with respect to a present preferred form which it may assume, it is not to be limited to such details and form since many changes and modifications may be made in the invention without departing from the spirit and scope of the invention in its broadest aspects. Hence, it is desired to cover any and all forms and modifications of the invention which may come within the language or scope of the appended claim.

I claim:

A supporting clip adapted to hold a tooth-brush which comprises two parallel, horizontally disposed members spaced apart a distance less than the thickness of the article to be supported, said members being formed at the ends thereof so as to provide projections extending horizontally outwardly from said clip, an arm connected to each of said projections extending downwardly from and inwardly of said members, the arms connected to adjacent projections of the two members being parallel to each other and forming a pair, the arms forming each pair extending toward the arms forming the other pair, curved portions formed at the lower ends of said arms, a longitudinally extending section connecting the lower ends of each of the pairs of arms of said clip, the section connecting one pair lying parallel to the section connecting the other

pair, both sections being disposed transversely to said members and being spaced apart from each other a distance less than the thickness of the article to be supported, said clip being formed of a single piece of resilient material bent into the specified shape, said clip being adapted to be adjustably connected to a tooth-brush, said arms being so formed that said members are urged toward each other and each section is urged toward the other when said clip is in engagement with a tooth-brush.

NATHAN A. OSCHER.
